(57) **CLAIM**

The ornamental design of a strength member used for a high threat blast wall, as shown and described.

DESCRIPTION

FIG. 1 is a top left front perspective view of a high threat blast wall showing my new design;

FIG. 2 is a bottom rear perspective view thereof;

FIG. 3 is a top left front explode perspective view showing the top and bottom portions separately;

FIG. 4 is a bottom rear exploded perspective view showing the top and bottom portions separately;

FIG. 5 is a top left front perspective view showing the bottom portion shown separately for clarity of illustration;

FIG. 6 is a bottom rear perspective view thereof;

FIG. 7 is a front elevation view thereof;

FIG. 8 is a rear elevation view thereof;

FIG. 9 is a left side elevation view thereof showing the upper fill port and lower fill port;

FIG. 10 is a right side elevation view thereof;

FIG. 11 is a top plan view thereof;

FIG. 12 is a bottom plan view thereof;

FIG. 13 is a top left front perspective view of the top portion shown separately for clarity of illustration;

FIG. 14 is a bottom rear perspective view thereof;

FIG. 15 is a front elevation view thereof;

FIG. 16 is a rear elevation view thereof;

FIG. 17 is a left side elevation view thereof showing the upper fill port and lower fill port;

FIG. 18 is a right side elevation view thereof;

FIG. 19 is a top plan view thereof; and,

FIG. 20 is a bottom plan view thereof.
